UNITED STATES PATENT OFFICE.

JOHN C. TALIAFERRO, OF BALTIMORE, MARYLAND, ASSIGNOR, BY MESNE ASSIGNMENTS, TO AMERICAN CAN COMPANY, OF JERSEY CITY, NEW JERSEY, A CORPORATION OF NEW JERSEY.

MACHINE FOR DRYING AND FLUXING METAL SHEETS.

SPECIFICATION forming part of Letters Patent No. 722,643, dated March 10, 1903.

Application filed November 24, 1900. Serial No. 37,600. (No model.)

To all whom it may concern:

Be it known that I, JOHN C. TALIAFERRO, a citizen of the United States, residing in Baltimore, in the State of Maryland, have invented a new and useful Improvement in Machines for Drying and Fluxing Iron, Steel, or other Metal Sheets Preparatory to Tinning the Same, of which the following is a specification.

10 My invention relates to fluxing-machines used in the manufacture of tin-plate.

It consists in the novel construction of parts and devices and in the novel combinations of parts and devices herein shown and 15 described, and specified in the claims.

In the accompanying drawings, forming a part of this specification, Figure 1 is a side elevation of a machine embodying my invention. Fig. 2 is a plan view, and Fig. 3 is a 20 central vertical longitudinal section.

In the drawings, A represents the frame of the machine.

B B are the drying and fluxing rolls, the same being hollow and steam-heated through 25 the steam-pipes C C' by which steam is admitted to the interior of the rolls.

D is the feed-table, the same having a series of converging rails d d upon which the sheets are placed and which operates as the 30 sheets are pushed forward over the same to partially scrape the water from their surface, owing to the fact that the rails converge or extend at an angle to the direction of movement along the feed-table. The feed-table is 35 further provided with side guides or gages d' d'', one of which, d'', is adjusted to and from its fellow d' by means of the brackets d'', furnished with a series of notches or holes d'', in which fit pins d'', by which this adjustable 40 gage is secured in place. These converging rails d on the feed-table serve to partially free the sheets from the water adhering to their surface as they are taken out of the water bath or vessel E and placed upon the feed-table.

The metal sheets are fed forward into the bite of the first pair of rolls B by means of a vibrating feeder, preferably consisting of a series of fingers F, secured to a rock-shaft F', 50 which is rocked at intervals, as required, by

means of cam f, through the lever f' and link f'', which connects with the arm f''' on the rock-shaft.

G is the flux bath or vessel, the same being furnished with a trap-discharge g, the upper 55 end or leg g' of which extends above the bottom of the vessel sufficiently to prevent the palm-oil or flux from flowing out, while at the same time it terminates sufficiently below the upper edge of the vessel to permit the water 60 which collects in the bottom of the flux vessel from the wet sheets passing through the machine to automatically discharge, the water of course being heavier than the oil and separating therefrom. The outer discharge 65 end g' of the trap extends up to a less height than the level of immersion of the rolls in the flux to keep the rolls from coming in contact with the water. The flux vessel G is supported by hooks g'' g''' from rods g'' on the 70 frame of the machine. The hooks g''' are spring-hooks to enable the vessel to be conveniently unhooked at one end when it is desired to empty it. Beneath the flux vessel G is a collecting vessel G' for overflowing oil 75 and water, the same having an upper faucet g'' for drawing off the oil and a lower faucet g''' for drawing off the water.

H is a counter arm or lever projecting into the path of the sheets between the fluxing- 80 rollers D D and D D, so as to be engaged by the sheets and register the same upon the counter mechanism H', with which the machine is provided for this purpose and which is operated by said counter-arm.

K is the tinning pot or vessel into which the sheets pass from the fluxing mechanism, and K' is a curved connecting-chute for delivering and deflecting the sheets from the fluxing mechanism into the tinning pot or 90 vessel. The chute K' is curved substantially on the quadrant of a circle, so as to receive and support the sheets as they issue horizontally from the fluxing-rolls and gradually turn or deflect them to enter the tinning-pot. It 95 is provided with vertically-extending sides to guide the sheets at their edges. The chute K' extends from the last pair of fluxing-rolls to the supplemental fluxing vessel M. The tinning pot or vessel K is provided with a 100

spout-shaped flux vessel M, open at both ends and projecting at its lower end into the molten tin k in the tinning-pot K and extending sufficiently beneath the surface of the molten 5 tin to enable the comparatively small amount of flux in the vessel M to stand at considerable height above the surface of the molten tin without spreading over its surface or causing the molten tin to overflow the pot K or 10 rise to too-great height therein, this action or operation being due to the great difference in specific gravity between the molten tin and the palm-oil or other flux. This secondary narrow or trough-shaped fluxing vessel M 15 thus combined with the tinning-pot operates, in connection with the fluxing-rollers D D and their flux vessel G, to insure the complete and perfect fluxing of every portion of the entire surface of each and every sheet passing 20 through the machine, as well as to completely expel from the surface of the sheet all water or moisture. This combination of parts also prevents all danger of and obviates all trouble from the flux on the molten tin in the 25 tinning-pot foaming or boiling over and catching fire, as has heretofore been experienced where the flux on the molten tin is permitted to spread over the whole surface of the molten tin in the tinning-pot. The secondary 30 open-ended fluxing vessel M has an overflow spout or passage M' near its upper end for the surplus flux collecting therein from the fluxed sheets as they pass into the tinning-pot. This overflow-discharge spout M' projects over the collecting vessel G', into which the surplus flux is discharged. The secondary or supplemental fluxing vessel M is also provided with curved or inclined guide-bars 35 N, which are hooked onto its upper edge and 40 serve to direct the metal sheets centrally and properly into the tinning-pot from the curved connecting spout or chute K'.

P is the driving-shaft, having a driving-pulley P' and suitable gearing p p communicating motion from it to the fluxing-rollers D, and the cam f, which operates the feeder, receives its revolving movement from one of the fluxing-rollers through the connecting-gearing p' p'. The gearing p p preferably 45 comprises a pair of bevel-gears, connecting spur-gears, sprocket gears and chains, as indicated in the drawings, and the gearing p' p' preferably consists of sprocket gears and chains. 50

55 I claim—

1. In a fluxing-machine, the combination with revolving, steam-heated fluxing-rollers, of a fluxing bath or vessel in which the lower fluxing-rolls revolve, a feed-table having converging rails for supporting the sheets and a feeder for pushing the sheets on said rails, a counter mechanism, a counter-arm projecting in the path of the sheets, a tinning-pot, a secondary contracted or spout-shaped flux vessel, open at both ends and projecting at its lower end into the tinning-pot, a curved chute for delivering and directing the sheets 60

from the fluxing-rolls into said secondary fluxing vessel, a collecting vessel, an overflow discharge-spout leading from said secondary fluxing vessel, and a trap discharge-pipe leading from the bottom of the main fluxing vessel and having its upper end or leg terminating below the upper edge of said main fluxing vessel, substantially as specified. 70

2. The combination with a fluxing vessel, of fluxing-rolls, a feed-table having rails for the sheets to rest upon extending at an angle to the direction of the movement of the sheets on the feed-table, and a feeder for pushing 80 the sheets along said rails, substantially as specified.

3. The combination with hollow fluxing-rolls, of means for heating said rolls, a fluxing vessel containing oil or flux in which the lower rolls revolve, and provided with a trap water-discharge for automatically separating from the oil or flux in the fluxing vessel the water which collects from the wet sheets passing between the fluxing-rolls, the outer leg of 85 the trap extending up to a less height than the level of immersion of the rolls in the flux to keep the water in the flux vessel out of contact with the rolls, substantially as specified. 90

4. The combination with hollow fluxing-rolls, of means for heating said rolls, a fluxing vessel containing oil or flux in which the lower rolls revolve, and provided with a trap water-discharge for automatically separating 100 from the oil or flux in the fluxing vessel the water which collects from the wet sheets passing between the fluxing-rolls, and a water-collecting vessel below the fluxing vessel, the outer leg of the trap extending up to a less 105 height than the level of immersion of the rolls in the flux to keep the water in the flux vessel out of contact with the rolls, substantially as specified.

5. The combination of fluxing-rolls with a fluxing bath or vessel below the rolls, a feed-table and feeder, a tinning-pot and a curved chute for receiving the sheets horizontally from the fluxing-rolls and delivering and deflecting them vertically into the tinning-pot, substantially as specified. 110

6. The combination of fluxing-rolls with a fluxing bath or vessel in which the lower rolls revolve, a feed-table and feeder, a tinning-pot, a curved chute for delivering and deflecting the sheets from the fluxing-rollers into the tinning-pot, and a supplemental narrow, open-ended flux-containing vessel projecting 120 at its lower end into the molten tin in the tinning-pot, substantially as specified. 115

7. The combination of fluxing-rolls with a fluxing bath or vessel in which the lower rolls revolve, a feed-table and feeder, a tinning-pot, a curved chute for delivering and deflecting the sheets from the fluxing-rollers into the tinning-pot, a supplemental narrow, open-ended flux-containing vessel projecting at the lower end into the molten tin in the tinning-pot, and an overflow discharge-spout at the 125

upper end of said supplemental fluxing vessel, substantially as specified.

8. The combination of fluxing-rolls with a fluxing bath or vessel in which the lower rolls revolve, a feed-table and feeder, a tinning-pot, a curved chute for delivering and deflecting the sheets from the fluxing-rollers into the tinning-pot, a supplemental, narrow, open-ended flux-containing vessel projecting at the

lower end into the molten tin in the tinning-pot, and guide-bars for the sheets in said supplemental fluxing vessel, substantially as specified.

JOHN C. TALIAFERRO.
